LIQUID SOAP DISPENSER

Robert L. Gruen, New York, N. Y., assignor to U. S. Sanitary Specialties Corporation, Chicago, Ill., a corporation of Illinois

Application June 22, 1956, Serial No. 42,002

Term of patent 14 years

(Cl. D4—3)

The back of the liquid soap dispenser is plain.

I claim:

The ornamental design for a liquid soap dispenser, substantially as shown and described.
